UNITED STATES PATENT OFFICE.

CHARLES E. ADAMSON, OF MARION, INDIANA, ASSIGNOR TO ADDRESSOGRAPH COMPANY, OF CHICAGO, ILLINOIS, A CORPORATION OF ILLINOIS.

DUPLICATING-MACHINE.

1,220,582.

Specification of Letters Patent. Patented Mar. 27, 1917.

Application filed June 14, 1909, Serial No. 502,039. Renewed February 2, 1917. Serial No. 146,259.

To all whom it may concern:

Be it known that I, CHARLES E. ADAMSON, a citizen of the United States, residing at Marion, in the county of Grant and State of Indiana, have invented certain new and useful Improvements in Duplicating-Machines, of which the following is a specification.

My invention relates to duplicating and printing machines, such as are particularly adapted for use in printing imitation type-written letters, but which may be arranged for direct printing if desired.

The primary object of my invention is the production of a machine of this type wherein provision is made for reciprocating a printing-carriage with respect to a type-form and whereby the impression-roller is controlled in its movements by the operator so that any size form may be printed without unnecessary motion of the printing-carriage.

Another object of my invention is the provision of a reciprocating printing-carriage having an impression-roller mounted therein and movable into and out of printing position and a movable operating-handle for reciprocating said carriage, said handle being operatively connected with the impression-roller so as to move said roller toward and from the type-form at any point within the range of movement of said carriage.

A further object is to provide improved mechanism for delivering the printed sheets from the machine and to so connect the same with the operating-handle that when the impression roller is moved away from the type-form, said delivery-mechanism is moved toward the type-form to act against the printed sheet and deliver the same from said form.

A still further object is to improve and simplify machines of this type, and to these ends, my invention consists in the combination and arrangement of devices and in the construction, arrangement, and combination of parts to be hereinafter described and particularly pointed out in the subjoined claims.

In the drawings,

Figure 1 is a side elevation of a machine constructed according to this invention.

Fig. 2 is a plan view of the same.

Fig. 3 is a central longitudinal section taken on line 3-3, Fig. 2.

Fig. 4 is a transverse section taken on line 4-4, Fig. 1, looking toward the left.

Fig. 5 is an enlarged vertical section through a portion of the machine taken on line 5-5, Fig. 4; the parts being in the position they assume during printing action.

Fig. 6 is a similar view with the parts in the position they assume after printing and while delivering the printed sheet from the type-bed.

Fig. 7 is a transverse section through the printing-carriage taken on line 7-7, Fig. 5.

Fig. 8 is an enlarged vertical section taken on line 8-8, Fig. 2.

Fig. 9 is a detached perspective view of the link connecting the handle with the crank-arm of the impression-roller and with the rock-shaft of the delivery-mechanism.

Fig. 10 is a detached perspective view of the eccentric spindle on which the impression-roller proper is held.

Fig. 11 is a detached perspective view of the delivery-mechanism.

Referring now to the drawings in detail, like letters of reference refer to like parts in the several figures.

The reference letter A designates the machine considered as a whole, and B a stand or support on which said machine is mounted. The stand or support comprises sides b, and an end wall b¹; said sides being grooved, as at b², for sliding engagement therewith of a paper-receiver C comprising a bottom c, a front wall c¹ extending from side to side of the support and a rear wall c², also extending from side to side of said support. The rear ends of the sides b of said support are connected by a rock member C³ fastened by means of screws C⁴ passing through the sides of said support and threaded into the ends of said rock-member so that the latter may be swung into the position shown in dotted lines in Fig. 3. The rock-member has secured to it a curved shield D of substantially U-shape which serves to direct the printed sheets from the machine into the paper-receiver C, as will be more clearly explained hereinafter.

E designates the frame or body of the machine which is mounted upon the stand or support B and comprises sides e including legs e¹ and a flat type-bearing bed e² connecting said sides and preferably formed integrally therewith; said bed being ribbed on its underside, as at e³, for the purpose of reducing the weight of the machine, yet providing the necessary strength to withstand the

strain during the printing operation. The sides e of said frame extend above the bed e^2 , and also extend beyond the ends of the same. At their upper edges, said sides are provided with inwardly-directed flanges e^4 , which latter and the bed e^2 form the upper and lower walls, respectively, of guide-grooves e^6 . Secured to the upper surface of the bed e^2 are chase-guides or retainers F formed of angle iron and extending from end to end of said bed. One of said guides has a friction-strip f secured to its upstanding member adapted to be engaged by the impression-roller, to be hereinafter described.

Located between the chase-guides or retainers F and resting upon the type-bed is a type-chase G which may be of any common construction and has a type-form g held therein, said form being formed of assembled type arranged in parallel rows, or consisting of electrotype, linotype slugs, or any other object or objects from which an imprint may be obtained by means of pressure exerted thereagainst. Between one of the sides of the type-chase and the adjacent guide or retainer F a paper-gage g^1 is interposed; said gage consisting of a flat strip of metal having one end reduced in width and bent over the type-chase, as at g^2 , Fig. 2. This paper-gage may be moved lengthwise so as to bring the bent end or stop g^2 at any desired point with reference to the length of the chase. I preferably employ as an inking-medium an inked ribbon H of considerable length and of a width to cover the type-form; and said ribbon is so arranged and its ends so connected that during the operation of the machine, it is moved lengthwise over the type-form. For this purpose I provide ribbon-rollers h , h^1 , one being located at each end of the machine, and to said rollers the opposite ends of the inked ribbon are secured. One of the ribbon-rollers has its ends mounted in a pair of aligned sockets h^2 secured to opposite sides of the frame; one of said sockets being preferably fixed while the other is formed on a spring arm h^3 secured to the side of the machine and adapted to normally retain the roller in position. Said spring arm also permits a ready removal of the roller owing to its flexibility which permits the socket carried thereby to be moved away from the co-operating end of the roller and thus permit the opposite end thereof to be withdrawn from the fixed socket. By grasping the roller when removed from its sockets and moving the same toward the rear end of the machine, or by raising the roller so as to lift the inked ribbon out of contact with the type-form, the chase G with its type-form can be easily removed from its supporting bed.

The roller h^1 at the opposite end of the machine, is also mounted in a pair of sockets

h^4 secured to opposite sides of the machine, one of said sockets being rotated by a pawl and ratchet-mechanism I and having one end of said roller so mounted therein that the latter is caused to rotate therewith. Said pawl and ratchet mechanism is adapted to be operated by the printing-carriage of the machine, in a manner to be more particularly described hereinafter.

The chase-guides F are separated from the sides of the frame by intervening spaces F^1 and in said spaces the side members j of a printing-carriage or carrier J are adapted to travel, as best shown in Fig. 4, said side members being connected by a cross-member j^1 having a pair of spaced rearwardly-extending ears j^2 to which is pivotally connected an operating-handle K adapted to be grasped by the operator. Said handle comprises a grip-member k arranged transversely a short distance in rear of the impression-member and in a plane above the same and side members k^1 extending forward from the grip-member and having upwardly extending ears k^2 which lie inside of the spaced ears j^2 and are connected to the latter by means of pivot bolts L^4 . The forwardly-extending side members k^1 of the handle are adapted to normally bear against the cross member j^1 of the carriage, thereby limiting the extent to which the handle may be lowered.

In the side members of the carriage, notches L are formed in which bearing-boxes l are located which are held in position by adjusting-screws l^1 threaded through the carriage above the notches L and having reduced lower portions l^2 passing through the bearing-boxes l and into bores l^3 formed in the carriage beneath the bearing-boxes. By reducing the lower portions of the adjusting-screws, shoulders l^4 are provided which are adapted to engage the upper faces of the bearing-boxes and hold the same down against the action of coil springs l^5 surrounding the reduced lower portions of said screws and entered in pockets l^6 on the underside of said boxes. Said springs bear at one of their ends against the inner ends of said pockets and at their other ends against the lower wall of the notches in which the bearing-boxes are held. Upon unscrewing the adjusting-screws, the springs l^5 act to elevate the boxes, and the screws serve to hold the boxes in the desired position. For the purpose of holding the adjusting-screws against rotation after being adjusted, wing lock-nuts l^7 are threaded onto the adjusting-screws and are adapted to bind against the upper surface of the printing carriage.

Mounted in said bearing-boxes are the eccentrically-arranged ends m of a spindle M on which an impression-roller M^1 is carried, and suitably fastened to or formed on said spindle is a crank-arm N having one end of

a link O pivotally connected thereto whose other end is secured to the swinging operating-handle, as at N¹; said link serving to compel the spindle M to rock in its bearings when the handle is actuated and owing to the ends of said spindle being eccentric to the main or body portion thereof on which the impression-roller M¹ is carried, said roller is caused to move toward and from the ribbon-covered type-form and simultaneously therewith is given a slight rotary movement.

The printing-carriage or carrier is adapted to be reciprocated upon the frame with the impression-roller in contact with the sheet of paper laid upon the ribbon-covered type-form during its rearward movement and for the purpose of obtaining free action for the carriage, two pair of guides or traction rollers P are rotatably secured to the sides j of the carriage or carrier and travel between the flanges e⁴ and the type-bearing bed e² of the frame, as best shown in Fig. 4. The rollers of each pair are alined and on opposite sides of the carriage and are slightly smaller in diameter than the spaces between said flanges and the bed so that during the forward movement of the printing-carriage, the front pair of rollers roll in contact with the underside of the flanges e⁴ while the rear pair of rollers roll in contact with the bed e² owing to the fact that during such forward movement the operating-handle is pressed downward to cause the impression-roller to be under pressure and in contact with the sheet of paper upon the ribbon-covered type-form, and consequently, the printing-carriage, which is elevated at the front and depressed at the rear, is guided in a perfect manner. During the rearward movement of the carriage, the operator draws rearward and upward on the operating-handle and the connection of said handle with the impression-roller causes the latter to be elevated into a plane out of contact with the sheet of paper printed during the forward movement of the carriage. The drawing of the handle upward and rearwardly causes the rear end of the carriage to be elevated so as to bring the rear pair of rollers in contact with the underside of the guide flanges e⁴ while the front pair of rollers roll in contact with the bed of the frame.

For the purpose of delivering the printed sheet from the ribbon-covered type-form during the rearward movement of the carriage, I mount upon the carriage a delivery-device, consisting of a transverse rock-shaft R having secured thereto eccentric collars r to which are fastened spring drag-arms r¹, the ends of which latter are in a plane above the type-form during the forward movement of the carriage and are adapted to be swung downward to engage the front edge of the

printed sheet during the rearward movement of the carriage; such change of position on the part of said drag-arms being accomplished through the rocking of the shaft R which has a pin r² extending therefrom and entering a swivel-block S secured to the link O and upon movement of said link, caused by the swinging of the operating handle, said pin is caused to move through an arc of a circle and thus compel the shaft R to rock. The relative arrangement of the delivery-device and the impression-roller is such, that when said roller is lowered into printing-position the spring drag-arms are elevated, and when said roller is elevated and out of printing position, said drag-arms are lowered so that they engage the front edge of the printed sheet of paper and force the rear end of the sheet in contact with the concaved surface of the shield whereby said sheet is turned and delivered into the paper-receiver underneath the frame of the machine.

Attention is called to the fact that the friction-strip f extends beyond both ends of the type-form and that the initial and final rotation of the impression-roller depends upon its contact with said strip; therefore, in starting the carriage forward from its extreme rearward position, the downward movement of the handle causes the impression-roller to be moved downward and in contact with the friction-strip before it comes in contact with the ribbon-covered type-form, thus starting rotation of said roller so that it will easily ride onto the ribbon-covered type-form, contact with which also aids in causing rotation of said roller, and as said friction-strip extends beyond the front end of the type-form, the roller is also continued in its rotary motion after it has passed over the end of the type-form. The inked ribbon is wound upon the ribbon-roller h step by step, owing to the fact that the carriage, as it approaches the rear end of its movement, engages the ratchet-mechanism I to give said ribbon-roller a slight rotation and as the ribbon-roller h at the opposite end of the frame is free to rotate, the ribbon is unrolled from the last-mentioned roller and wound upon the rollers h¹.

The operation of the machine is as follows:—

Normally the printing-carriage or carrier is at the rear end of the machine so that the ribbon-covered type form is exposed to permit the ready placing of a sheet of paper thereon. The operating-handle is then grasped and pressed downward to cause the impression-roller to move into contact with the friction-strip at the rear end thereof and simultaneously with this movement the eccentrically-mounted drag-arms I are elevated. The carriage is now forced forward

so as to pass over the sheet of paper with the desired pressure, the extent of movement of said carriage being controlled by the operator and being just sufficient to clear the front end of the sheet of paper so that the drag-arms may be lowered upon return movement of said carriage directly in advance of said front end. In drawing the carriage backward, the tendency is to swing the operating-handle upward and this action causes the impression-roller to be elevated and the drag-arms to be lowered; said drag-arms engaging the front edge of the paper and drawing the sheet of paper back over the rear edge of the type-form into engagement with the curved shield D, which, as stated, causes said sheet to be turned about and delivered into the paper-receiver underneath the type-bearing member. As the carriage approaches the end of its rearward movement it engages the ratchet-mechanism I, which may be of any common construction, and causes the inked ribbon to be wound upon the ribbon-roller h¹. The reciprocating movement of the carriage or carrier is continued until the desired number of sheets of paper have been printed and during such time the ribbon is wound upon the ribbon roller h¹ step by step so as to assure perfect imprint for all the sheets.

By reason of the operator having absolute control of the extent to which the carriage must be moved, sheets of paper or cards of any size may be printed without compelling the carriage to travel through its full range of movement, thus avoiding unnecessary wear on the parts, preventing unnecessary movement of the carriage, and considerably increasing the capacity of the machine.

Having thus described my invention, what I claim is:

1. The combination of a type-bearing member, an impression-member coöperating therewith, an inking-device, a curved shield located at one end of said type-bearing member and pivotally secured to permit of its swinging downward, and paper delivery-mechanism adapted to move the printed paper against said shield and deliver the same underneath said type-bearing member.

2. The combination with a support having a paper-receiver, of a type-bearing member mounted on said support, above said paper-receiver, an impression-member coöperating with said type-bearing member, an inking-device, a curved shield located at one end of said support and pivotally connected therewith so as to swing thereon, and paper-delivery mechanism adapted to move the printed paper against said shield and deliver the same into said paper-receiver.

3. The combination of a type-bearing member, a carrier traversing said member, an impression-member journaled in said

carrier, an inking-device, delivery-mechanism carried by said carrier and operatively related to said impression-member, a movable handle on said carrier operatively connected with said delivery-mechanism and 70 said impression-member and adapted to cause the impression-member to be moved into and out of printing position and the delivery-mechanism into and out of delivering position.

4. A type-bearing member, a carrier traversing said member and having sides held against swinging movement, an impression roller journaled directly in said sides, and an inking device, the whole acting to print 80 upon a sheet of paper; combined with a movable operating handle operatively connected with said impression-roller to cause the same to be moved into and out of printing position and to move said carriage relative to 85 said type-bearing member.

5. The combination of a type-bearing member, a carrier traversing said member, an impression member mounted in said carrier and coöperating with said type-bearing 90 member said impression member being adapted to be raised and lowered, a pivoted operating handle, a connection between said handle and said roller whereby the latter is caused to rise and lower independent of said 95 carrier, an inking device and means controlled by said operating-handle for delivering the printed paper from said type-bearing member.

6. The combination of a type-bearing 100 member, a carrier traversing said member and having fixed sides, an impression-roller journaled directly in said fixed sides and coöperating with said type-bearing member, an inking device, and means for moving said 105 impression-roller toward or from said type-bearing member independent of said carrier and at any point within its range of movement and for moving said carrier relatively to said type-bearing member.

7. The combination of a type-bearing member, a carrier traversing said member and having fixed sides, an impression-roller journaled directly in said fixed sides and coöperating with said type-bearing member, 115 an inking device, and means to cause the said impression-roller to move into printing position independent of said carrier when moving said impression-roller over an unprinted sheet placed upon said type-bearing 120 member and for moving said impression-roller out of printing position independent of said carrier when moving said impression-roller in to its position for printing a second sheet.

8. The combination of a type-bearing member, an impression member coöperating therewith and movable into or out of printing position, a carrier having fixed parts in which said impression-member is journaled 130

- directly, an inking device, a movable member attached to said carrier and to which member, the force or power is applied for moving said carrier, and operative connections between said movable member and said impression-member to cause the latter to be moved into and out of printing position independent of said carrier.
9. The combination of a type-bearing member, a carrier reciprocating on said member and having fixed parts, an impression-roller journaled directly in said fixed parts and arranged for movement into and out of printing position, an inking-device, a pivoted handle connected to said carrier and movable in opposite directions when said carrier is reciprocated, and operative connections between said pivoted handle and said impression-roller through the agency of which said impression-roller is moved into and out of printing position independent of said carrier during the opposite movements of said movable member.
10. The combination of a type-bearing member, a reciprocating-carriage having fixed sides and having also a movable handle whereby said carriage is reciprocated and which is moved in opposite directions when causing said carriage to reciprocate, an impression-roller journaled directly in said fixed sides and movable toward and from said type-bearing member, an inking-device, and operative connections between said movable handle and said impression-roller to cause the latter to move toward or from said type-bearing member independent of said carrier.
11. The combination with a type-bearing member, a traveling carriage having fixed sides, an impression member journaled in the fixed sides of said carriage and movable into and out of printing position, an inking-device, and a pivoted element on said carriage for actuating the same adapted to swing in opposite directions and having connection with said impression-member, movement of said pivoted element in one direction causing said impression-member to move into printing position independent of said carriage and movement of said pivoted element in the opposite direction causing said impression-member to move out of printing position independent of said carriage.
12. Two coöperating members, one a traveling carrier having fixed sides and an impression roller journaled in said fixed sides and the other a flat type-bearing member; combined with an inking-device and a pivoted member on said carrier to which power is applied to cause said carrier to travel, said movable member having connection with said impression-roller to move the same into and out of printing position independent of said carrier.
13. Two coöperating members, one a reciprocating carrier having fixed sides and an impression roller journaled in said fixed sides and the other a type-bearing member, said impression-roller being movable toward and from said type-bearing member; combined with an inking-device, a swinging handle on said carrier to be grasped by the operator for reciprocating said carrier and having its center of movement independent of said impression roller, and an operative connection between said swinging handle and said impression-roller to cause the latter to be moved toward said type-bearing member independent of said carrier when forcing the latter in one direction and to be moved from said type-bearing member independent of said carrier when drawing the latter in the opposite direction.
14. The combination with a type-bearing member, a carrier having fixed sides and being mounted for reciprocating movement on said type-bearing member and adapted to be pushed in one direction and pulled in an opposite direction, an impression-roller journaled in the fixed sides of said carrier and movable into and out of printing position, an inking-device, a pivoted handle on said carrier to be grasped by the operator and to swing in one direction when pushing the carrier forward and in the opposite direction when pulling the carrier rearward, said pivoted handle being mounted at a point independent of said impression roller, and an operative connection between said handle and said impression-roller to cause the latter to be moved into and out of printing position independent of said carrier.
15. The combination of a type-bearing member, a traveling carrier, an impression roller mounted in said carrier, an inking device, an operating handle for causing said carrier to travel pivotally connected to said carrier, and operative connection including an eccentric between said impression roller and said operating handle whereby the swinging movement of said handle causes said impression roller to move toward and from said type-bearing member.
16. The combination of a type-bearing member, a carrier mounted for reciprocating movement on said type-bearing member, an impression-member eccentrically mounted in said carrier, an inking-device, an operating-handle located in rear of said impression-roller and in a plane above the same, said handle being pivotally secured to said carrier and adapted to be swung downward and forward when moving said carrier in one direction and to be drawn upward and rearward when moving said carrier in its opposite direction, and operative connection between said handle and said impression-roller to cause the latter to move into and out of printing position.

17. The combination of a type-bearing member, a carriage mounted for movement thereon and provided with aligned notches at opposite ends, bearing-boxes arranged in said notches, an impression-roller mounted in said bearing-boxes, adjusting-screws adjustable in said carriage and passing through said bearing-boxes, said adjusting-screws having reduced lower portions to provide shoulders, and springs serving to hold said bearing-boxes against the shoulders of said adjusting-screws.
18. The combination of a type-bearing member, a traveling carriage thereon having side members provided between their upper and lower ends with openings, bearing-boxes set into said openings and having bores extending from their upper to their lower faces, said bores being enlarged at their lower ends, an impression-roller mounted in said bearing-boxes, an inking-device, adjusting-screws passing through the portions of said carriage above said openings and entering the portions of the carriage below said openings, said adjusting-screws extending through the bores of said bearing-boxes, and coil-springs surrounding said adjusting-screws and bearing at one of their ends against the inner ends of the enlarged lower portions of said bores and at their other ends against the lower walls of said openings.
19. The combination of a type-bearing member, a traveling carrier thereon, an eccentrically-mounted spindle in said carrier, an impression-roller on said spindle, a crank-arm carried by said spindle, a movable operating-handle, a link connecting said handle with said crank-arm, and an inking-device.
20. The combination of a type-bearing member, a reciprocating carriage on said member, an eccentrically-mounted impression-roller in said carriage, a crank-arm secured to the spindle of said roller, an operating-handle pivoted to said carriage, a link connecting said operating-handle with said crank-arm, a swivel-block on said link, a delivery-device including a rock-shaft having a pin extending therefrom and entering said swivel-block, and an inking-device.
21. The combination of a type-bearing member, a reciprocating carriage mounted thereon and comprising side-members and a cross-member connecting said side-members, an impression-roller eccentrically-mounted in said side-members, a crank-arm extending from the spindle of said impression-roller, an operating-handle having a transverse grip member and side members extending forward therefrom and provided with upward extensions pivotally connected to the cross-member of said carriage, the forward ends of the side-members of said handle being adapted to strike the cross-member of said carriage to limit the movement of said handle in one direction, a link connecting said crank-arm with said operating-handle, and an inking-device.
22. A type-bearing member, a carrier having fixed sides and being confined to movement conforming to the surface of said type-bearing member, an impression roller journaled in the fixed sides of said carrier and movable into and out of printing position, and an inking device; combined with a movable operating handle to move said carrier with respect to said type bearing member, said handle being operatively connected with said impression-member to cause the same to be moved into and out of printing position.
